ATTORNEY.

UNITED STATES PATENT OFFICE.

LEWIS T. WRIGHT, OF KESWICK, CALIFORNIA.

ROASTING-FURNACE.

SPECIFICATION forming part of Letters Patent No. 697,062, dated April 8, 1902.

Application filed July 24, 1901. Serial No. 69,588. (No model.)

To all whom it may concern:

Be it known that I, LEWIS T. WRIGHT, a subject of the King of Great Britain, residing at Keswick, in the county of Shasta and State 5 of California, have invented certain new and useful Improvements in Roasting-Furnaces, of which the following is a specification.

My invention relates to improvements in that class of roasting-furnaces described in 10 my United States Patent No. 629,023, dated July 18, 1899. In said patent I show and describe an outer hollow shaft carrying the stirring-arms, an open-bottomed pipe in said shaft, and an intermediate pipe in said shaft, 15 which intermediate pipe was therein shown and described as having a closed bottom. I have discovered that if the intermediate pipe be made open at the bottom the water will still continue to circulate substantially in the 20 same direction as before when said pipe was closed at the bottom—that is to say, when said intermediate pipe is open at the bottom the water discharging from the innermost pipe will not now pass through said open bottom 25 of the intermediate pipe, and thus up through the hollow shaft, without traversing the arms, but will continue to travel up the intermediate pipe to the inner arms, thence outward and back through the outer arms, and then 30 up through the hollow shaft. I do not say that absolutely the whole of the water thus passes radially along the arms and back again; but at least sufficient water so passes to produce the necessary cooling effect. This construction is found to be particularly advantageous when the water used for cooling the 35 apparatus contains a large proportion of solid matter in suspension.

In the accompanying drawings, Figure 1 is 40 a broken central vertical section of the apparatus, showing the hollow shaft and the stirring-arms in side elevation; and Fig. 2 is a vertical section of the lower portion of the hollow shaft, the innermost pipe, and the intermediate pipe.

Referring to the drawings, 1 represents the furnace proper, having the hollow outer shaft 2, the innermost pipe 3, and the intermediate pipe 4. Said hollow outer shaft carries the 45 hollow stirring-arms 5, upon which are secured the rabbles 6. Within said stirring-arms 5 are branch pipes 7, open at the end

and discharging into the hollow stirring-arms, said pipes 7 being supported in said stirring-arms by spiders 8. 9 is a feed-water pipe 55 leading to the innermost pipe, and 10 is an exhaust-pipe leading from the hollow shaft.

The whole of the above construction is precisely the same as that shown in the patent above referred to, and therefore need not be 60 more particularly described, the only exception being that the intermediate pipe is now open at the bottom, as shown at 11, instead of closed, as formerly. I find that notwithstanding the lower end of the intermediate 65 pipe being open the water will tend to travel in the same direction as formerly, this being due to the suction up said intermediate pipe by the heating of the water within the stirring-arms. This construction is advanta- 70 geous, in that it permits said pipes to be very easily cleaned, which is of particular importance when the water used contains a large quantity of sand or other solid matter in suspension. 75

I claim—

1. In a roasting-furnace, the combination, with a series of floors, of a central hollow shaft, hollow arms carried thereon over the respective floors, an open-bottomed pipe inserted in said shaft, a second open-bottomed pipe in said shaft into which the first pipe discharges intermediate to said first pipe and shaft, open-ended pipes leading from the intermediate pipe into the hollow arms, and 80 feed and exhaust pipes connected to the first pipe and hollow shaft, substantially as described.

2. In a roasting-furnace, the combination, with a series of floors, of a central hollow 90 shaft, hollow arms carried thereon over the respective floors, an open-bottomed pipe in said hollow shaft, open-ended pipes leading from the said open-bottomed pipe into the hollow arms, a feed-pipe to the open-bottomed 95 pipe, and an exhaust-pipe from the hollow shaft, substantially as described.

In witness whereof I have hereunto set my hand in the presence of two subscribing witnesses.

LEWIS T. WRIGHT.
